UNITED STATES PATENT OFFICE.

FRED PELTON, OF INDIANAPOLIS, INDIANA.

WATER-HEATER FOR COOKING-STOVES.

No. 841,811.

Specification of Letters Patent.

Patented Jan. 22, 1907.

Application filed August 28, 1905. Serial No. 276,094.

To all whom it may concern:

Be it known that I, FRED PELTON, a citizen of the United States, residing at Indianapolis, in the county of Marion and State of Indiana, have invented certain new and useful Improvements in Water-Heaters for Cooking-Stoves, of which the following is a specification, reference being had therein to the accompanying drawings.

10 This invention relates to an improved water-heating attachment for cooking-stoves, hereinafter described, and particularly pointed out in the claims.

15 The object of this invention is to provide a simple and cheap water-heating attachment for cooking-stoves which is intended to be substituted for the end-lining of the fireplace or fire-pot of cooking-stoves, which hollow lining or heater is constructed to be applied 20 to any form of cooking-stove without encroaching on the fire-space of the fireplace of the cooking-stove to which it is applied or interfering with the combustion of the fuel. I attain this object by means of the heating 25 apparatus illustrated in the accompanying drawings, in which similar numerals of reference designate like parts throughout the several views.

30 Figure 1 is a broken view of a cooking-stove, showing my attachment or hollow lining applied thereto. Fig. 2 is a detail view of the heating attachment or hollow liner looking in the direction of the arrow *a*. (See Figs. 1 and 3.) Fig. 3 is a detail top view of 35 the same, and Fig. 4 is a detail view of the same looking in the direction of the arrow *b*. (See also Figs. 1 and 3.)

1 designates a cooking-stove of the usual or any type provided with a fireplace or fire-pot 2, at one end of which is situated my water-heating attachment or hollow liner.

45 The water-heating attachment or water-liner is composed of the inner hollow heat-absorbing liner 3, which is substituted for the usual metal end-liner and has its edges formed similar to the end-liner for which it is substituted to equally fit in place in the fireplace (see particularly Fig. 2) between the back or back-liner and the front grate thereof 50 and against the outer wall of the stove.

The reduced projecting door-closing portion 4 of the heater is formed to fit in the end door-opening of the stove and to project therethrough, (see particularly Fig. 4,) 55 which projected portion fits into said door-opening and serves as a steadyng and sup-

porting means for the heater. A hand-hole plate 5 covers the hand-hole opening 5^h of the outer projecting portion 4 of the heater and is removably secured in position over 60 said hand-hole by means of a bolt 6, passing through the bridge 7, or other suitable securing means.

A horizontally-extending heater-pipe 8 is 65 screwed into the inner side of the liner portion 3 of the heater to project outwardly therefrom, and the said pipe or tube 8 has its mouth or inner open end situated directly opposite the center of the hand-hole 5^h, so that when the hand-hole cover 5 is removed 70 easy access may be had to the interior of the tube 8 to remove the lime or other deposit therefrom.

A cold-water-circulating pipe is connected 75 at one end to the bottom of the boiler 9 and extends therefrom to be connected to the heater, which heater end of the pipe is screwed into the lower boss 11, formed in the outer bottom side of the reduced projecting door-closing portion 4 of the heater. A pipe 80 12 extends from the boss 13, formed on the top outer side of the reduced projecting door-closing portion 4 of the heater, wherein it is screwed, and extends therefrom to the top of the boiler 9, to which it is connected. 85

During warm weather, when it would be uncomfortable to maintain the usual coal fire in a cooking-stove, an auxiliary gas-burner 14 is placed within the fireplace of the stove, to be situated directly under the tube 8, and 90 said burner is connected to the gas-service pipes by means of a feed or supply pipe 15, which pipe is provided with a suitable shut-off valve 16.

A hood or deflecting-shield 17 is provided 95 to inclose the tube 8 and rests upon the grates 18 of the stove, and the said hood is provided for the purpose of not only directing the flame around the heater-tube 8, but also for deflecting the flame toward and against 100 the inner side of the hollow lining 3 to heat the water in the heater. A gap between the top of the hollow liner 3 or the water-heater and the top portion of the deflector-hood 17 is provided for the purpose of permitting the 105 escape of the products of combustion from within the deflecting-hood.

A stop-valve 19 is situated on the end of the pipe 12 next the boiler 9, and another stop-valve 20 is situated on the pipe 12 between the valve 19 and the heater. A stop or drain valve 21 is connected to the cold-

water pipe 10 between the bottom of the boiler 9 and the heater, and said valve 21 is provided with a drip 22, which drip is designed to permit the draining of the water from the heater when the valves 19 and 21 are closed. Now when it is necessary to apply a cleaning compound to the heater and the connecting-pipes thereof the valves 19 and 21 are first closed and the valve 20 is opened. The water confined in the pipes and in the heater escapes through the drain-valve 22, after which a suitable cleaning compound is introduced into the heater by means of the funnel 23, which operation when completed the valve 20 is closed and the valves 19 and 21 are opened to permit the circulation of the water through the cold-water or feed pipe to the heater and from thence through the hot-water-circulating pipe 12 to the top of the boiler 9.

Having thus fully described this my invention, what I claim as new and useful, and desire to cover by Letters Patent of the United States therefor, is—

1. In a water-heating attachment, the combination with the fireplace of a cooking-stove, an inner water-heating end-liner having an outer door-closing portion, the outer hollow door-closing integral portion of said liner provided with a hand-hole opening situated centrally of its outer face, of a horizontally-projecting inner tube connected to said inner heating end-liner and situated directly opposite said hand-hole opening, a water-boiler, a cold-water pipe extending from said boiler and connected to the outer bottom portion of said closing integral portion of said end-liner, and a hot-water pipe extending from the top of the outer portion of said liner to connect to the top of said boiler.

2. In a water-heating attachment, the combination with the fireplace of a cooking-stove, an inner water-heating end-liner hav-

ing an outer door-closing portion, the outer hollow door-closing portion of said liner provided with a hand-hole opening situated centrally of its outer face, of a horizontally-projecting inner tube connected to said inner heating end-liner and situated directly opposite said hand-hole, a water-boiler, a cold-water pipe extending from the bottom of said boiler and connected to the outer bottom portion of said outer door-closing portion of the heater, a hot-water pipe extending from the top side of said door-closing portion of said heater to connect to the top of said boiler, a heating-burner situated within said fireplace under said heating-tube and a deflecting-hood inclosing said tube and said burner.

3. In a water-heating attachment, the combination with the fireplace of a cooking-stove, an inner water-heating end-liner having an outer door-closing portion, the outer door-closing integral portion of said liner provided with a hand-hole opening situated centrally of its outer face, of a horizontally-projecting inner tube connected to said inner heating end-liner and situated directly opposite said hand-hole, a water-boiler, a cold-water pipe extending from the bottom of said boiler and connected to the outer bottom portion of the outer door-closing portion of said heater, a hot-water pipe extending from the top side of the outer door-closing portion of said heater and connected to the top of the boiler, suitable cut-off valves on said upper and lower water-circulating pipes, means for draining said lower pipes, and a funnel on said upper circulating-pipe whereby a deposit or scale removing fluid is supplied to the heater.

In testimony whereof I affix my signature in presence of two witnesses.

FRED PELTON.
